UNITED STATES PATENT OFFICE.

JOHN S. BAKER, OF CHICAGO, ILLINOIS, ASSIGNOR TO THE COOK ELECTRIC COMPANY, OF CHICAGO, ILLINOIS, A CORPORATION OF ILLINOIS.

ELECTRIC SWITCH.

Application filed October 23, 1922. Serial No. 596,225.

My invention relates to electric switches and it has special reference to protective switches that are automatically releasable to open an associated electric circuit when abnormal heat conditions obtain therein.

More particularly my invention pertains to electric switches of the aforesaid character that are adapted to be restored to operative condition after the abnormal heat conditions, causing release of the switch, have discontinued, making it safe to permit again the flow of electric current in the circuit. Many electrical devices, and particularly electrical heating devices such as flat irons, 10 cookers and the like, are liable to become overheated because of neglect to turn off the electric current after the devices have been used or for other numerous reasons. The overheating of electrical devices and those 20 particularly used for household purposes frequently causes the devices themselves to burn up besides scorching or setting fire to adjacent materials.

An object, therefore, of my invention is 25 to provide an electric switch which will be automatically opened when abnormal heat conditions or temperatures obtain in the apparatus to which my switch is applied. Moreover, by means of my present invention, 30 the electric circuit after being opened because of abnormal heat conditions, is not likely to be closed through the agency of my switch until the excess heat has been dissipated which then allows my switch to 35 be restored to operative condition.

Another object of my invention is to provide a resoldering switch that is capable of being manually reset to close the electric circuit only when the abnormal heat obtain- 40 ing in the associated electrical device has become dissipated to a point where the resoldering holding-in element becomes frozen thereby allowing my switch to be reset into operative condition.

A further object of my invention is to 45 provide a switch such as I have outlined above in which the heat responsive or fusible element thereof is in very close thermal relation to the heating element so as to respond in a very short time to any abnormal temperature obtaining in the heating element. Since my switch is maintained in operative condition only when the resoldering or fusible element is frozen or in normal 50 condition, it is quite obvious that my switch

can not be reset to close the circuit through the associated electrical device unless it is cooled below the danger point.

Another object of my invention is to provide a switch of the foregoing character 60 which will be simple and economical to construct and efficient in operation.

Other objects and novel features of my invention will be hereinafter pointed out, and for a better understanding thereof, reference may be had to the following description and the accompanying drawings, in 65 which—

Figure 1 is a view in elevation of an electrical device, such as a flat-iron equipped 70 with an electric switch embodying a form of my invention;

Fig. 2 is a view in elevation of a form of my improved electric switch having its cover plate removed to expose the internal mechanism thereof in on-position;

Fig. 3 is a view similar to Fig. 2 excepting that the mechanism is shown as occupying off-position;

Fig. 4 is a plan view of the electric switch 80 of Figs. 2 and 3;

Fig. 5 is a view partially in elevation and partially in section taken approximately along the line 5—5 of Fig. 2 and showing in section a portion of the electric iron of 85 Fig. 1;

Fig. 6 is a view taken approximately along the line 6—6 of Fig. 2;

Fig. 7 is a detail view showing a heat responsive or fusible element that may be 90 comprised in my switch mechanism; and

Fig. 8 is a view showing the contact members of the electrical device of Fig. 1.

For convenience, I have illustrated in Fig. 1 an electric flat-iron 10 which is provided 95 with a usual plug connector 11 that serves to connect the current-conducting leads 12 to the heating element of the flat-iron 10. A handle 13 is supported upon a member 14 secured to the flat-iron 10 by means of screw 100 bolts 15. An opposed push button electric switch 16 is mounted upon the spring support 14 immediately adjacent to the plug connector 11. It is to be understood that the electric switch 16 is independent of the plug connector 11 and is connected in circuit intermediate the plug connector 11 and the heating element of the iron 10.

The electric switch 16, as shown in Figs. 2, 3 and 4, is provided with two opposed 110

- push buttons 17 and 18 that are severally positioned on each side of the handle support 14 of the flat-iron 10. In this manner, the electrical switch 16 may be manually actuated with great convenience without removing the hand from the handle 13. The switch of Fig. 2 shows the opposed push buttons occupying their on-position, and Fig. 3 shows them occupying off-position.
- 10 The opposed push buttons 17 and 18 project through insulating members 19 and 20, respectively, that are mounted upon the casting 21 which houses the switch mechanism. When the cover plate is applied to the mechanism of Fig. 2, the electric switch is completely housed, this cover plate being secured to the switch casing 21 by means of screws that may be threaded into the holes 22.
- 15 20 The push buttons 17 and 18 are oppositely secured to a central cross-piece 23 which is adapted to slide to and fro in accordance with the actuation of the push buttons. A guide plate 24 is positioned behind the cross-piece 23 and is provided with upstanding lugs 25 and 26 that project through openings 27 and 28, respectively, formed in the cross-piece 23. The guide plate 24 is also provided with spaced upstanding lugs 29 and 30 formed at its lower portion. The guide plate 24 is, therefore, supported upon the cross-piece 23 by means of the lugs 25 and 26 and in addition is adapted to move in conjunction therewith.
- 25 30 35 A helical spring 31 is positioned intermediate the upstanding lugs 25 and 26 and the upstanding lugs 29 and 30, and is secured at its lower end 32 to a latching member 33 and at its upper end as shown in Figure 5 to an eyelet 34 formed on the cross-piece bridging the two portions of a rocker-arm 35. The spring 31 constitutes an off-and-on center spring and is adapted to oscillate the rocker-arm 35 which is pivoted upon ears 36 and 37 that are struck up from a supporting bracket 38 integrally formed on a rear supporting plate 39. An electrical contact member 40 in the form of a sectional cylinder is mounted upon the rocker-arm 35 but is insulated therefrom by means of a mica cylinder 43.
- 40 45 50 The latch 33 is provided with an ear 33a that projects through a slit 42 formed in the lower portion of a floating lever 44 that is provided at its upper end with two projections 45 and 46 that extend through openings as at 47, formed in a stationary supporting member 49, as shown particularly in Figs. 4 and 5. The latch 33 is normally adapted to engage teeth 50 formed upon a heat responsive element 51 that is soldered to a cylindrical pin 53 (see Fig. 7) secured to the rear plate 39.
- 55 60 65 The heat responsive element 51, as shown in Fig. 7, constitutes a cylindrical rotatable member 52 upon the exterior of which the teeth 50 are formed. The threaded pin 53 serves as a support for the cylindrical member 52 and is secured thereto by means of a fusible or soldered connection 54. As long as the soldered connection 54 maintains its solid state or is frozen, the cylindrical member 52 is held against rotation upon the pin 53. However, when the connection 54 becomes liquefied or the solder softens, the cylindrical member 52 is then free to rotate upon the pin 53.
- 70 75 80 85 90 95 100 105 110 115 120 125 130 The contact member 40, mounted upon the oscillating rocker-arm 35 is adapted to engage a cooperating spring contact member 55 that is shown in Fig. 4 as extending transversely of the switch mechanism and connected to a conducting member 56 by means of a screw 57. The electrical contact member 40 is also adapted to engage a second and adjacent stationary spring contact member 58 that is secured to a conducting member 59 by means of a screw 60. As shown in Figs. 4 and 5 the contact member 40 is adapted to bridge the space between the stationary contact members 55 and 58 of my electric switch and when in the position shown in Fig. 2, serves to bridge the contact members 55 and 58 and thereby connects the conducting member 56 to the conducting member 59. When the contact member 40 occupies the position shown in Fig. 3, the contact members 55 and 58 are disconnected from each other and the electric circuit through the switch is broken.
- 100 105 110 115 120 125 130 As shown in Figs. 4 and 5, the contact member 55 is connected to the conducting member 56 that is insulated from the rear plate 39 by means of interposed insulating material 61. Similarly, the contact member 58 and the conductor 59 are likewise insulated from the rear plate 39 but spaced from the conductor 56, as shown in Figs. 2 and 3. An insulating member 61a serves to insulate the conductors 56 and 59 at their rear. The conductor 59 is connected by means of a connector 62 to one terminal 63 of a heating element 64 which is embedded in the body 65 of the flat-iron. The other conductor 66 of the heating element is connected by means of a connector 67, as shown in Fig. 8, to one of the terminals 68 of the flat-iron. The conductor 56 of the electric switch is connected in any suitable manner, preferably such as a strap 69 to another terminal 70 of the flat-iron.
- 110 115 120 125 130 It will thus be observed that the conductor 59, in addition to being electrically connected to the heating element 64 of the flat-iron, is likewise in close thermal relation thereto. Again, the heat responsive element 51 is placed in proximity to the conductor 59 and, is, therefore, in very close thermal relation to the heating element of the flat-iron. Moreover, the heat responsive ele-

ment 51, in addition to being in heat conductive relation to the heating element of the flat-iron, is also in very close convective relation to the flat-iron by reason of its being located in the lower portion of the electric switch 16.

The plug connector 11 is adapted to engage the contact members 68 and 70 of Fig. 8.

10 From the foregoing description, it will be observed that the electric switch of my invention is interposed in the electric circuit intermediate the plug connector 11 and the heating element 64 of the flat-iron and, therefore, is operative to open or close the electrical circuit in response to the action of the heat responsive element 51.

When my electric switch is applied to a heating device, such as the flat-iron 10 of Fig. 1, the heat responsive element 51 which, in this instance, is shown as being a self-soldering device and comprising a rotatable ratchet wheel 52 is in close thermal relation to the heating element 64 of the iron. Should the temperature of the heating element become excessive the soldered connection 54 will liquefy, thereby permitting the ratchet wheel 52 to rotate relative to the pin 53. In this circumstance, the latch 33 is released and the floating lever 44 is moved from the position it occupies in Fig. 2 to the position it occupies in Fig. 3. Simultaneously therewith the off-and-on center spring 31 is moved and when it passes the pivotal center of the rocker-arm 35, the rocker-arm 35 will be moved to open position, as shown in Fig. 3. When the rocker-arm 35 is in this position the contact member 40 has interrupted the electric circuit between the stationary contact members 55 and 58. As a result, the electrical circuit through the iron 10 is immediately interrupted. Operation of the opposed push buttons 17 and 18 will cause the floating lever 44 to oscillate, but the latch 33 will not be retained by the teeth 50 on the ratchet wheel 52 of the heat responsive element 51 unless the soldered connection 54 has, in the meantime, become solidified. Of course, the soldered connection 54 will not solidify until the temperature thereof has been lowered below the danger point. By varying the composition of the soldered connection 54, the temperature at which it will liquefy may be regulated. In the event that the soldered connection 54 has solidified, actuation of the opposed push buttons 17 and 18 will cause the latch 33 to engage the ratchet wheel 52 and permit relocation of the floating lever 44 to on-position which it occupies in Fig. 2.

When the floating lever 44 occupies the position shown in Fig. 2, the electrical contact 40, mounted upon the rocker-arm 35, may be actuated to open and close the electrical circuit between the contact members

55 and 58 at will. In this condition, the electrical contact 40 acts as in any other electric switch.

When the floating lever 44 occupies the position shown in Fig. 3, the latch member 33 is precluded from disengaging therefrom by reason of the slot through which the latch 33 projects, being so proportioned that the latch can not be drawn through the opening when positioned longitudinally of the floating lever 44.

While I have shown and described in detail one embodiment of my invention, it is to be understood that many modifications may be made therein without departing from the spirit and scope of the appended claims.

What I claim as new and desire to secure by Letters Patent of the U. S. is:—

1. An electric switch comprising a movable contact member, an off-and-on center spring connected thereto at one of its ends for positioning said contact member either in on-position or off-position, a latch connected to the other end of said spring for normally holding it under tension, and a fusible element normally holding said latch in operative position whereby said spring is retained under tension, said fusible element when abnormally heated releasing the tension in said spring thereof thereby permitting said spring to move said contact member of off-position.

2. An electric switch comprising a movable contact member, an off-and-on center spring connected thereto for positioning said contact member either in on-position or off-position, a latch connected directly to and carried by said spring normally holding it under tension, and heat responsive means normally holding said latch in operative position whereby said spring is retained under tension, said heat responsive means when raised to an abnormal temperature releasing the tension in said spring thereby permitting the automatic moving of said contact member to off-position.

3. An electric switch comprising a movable contact member, an off-and-on center spring connected thereto at one of its ends for positioning said contact member either in on-position or off-position, a latch connected to the other end of said spring normally holding it under tension, and heat responsive means for controlling the position of said latch and the consequent degree of tension in said spring.

4. An electric switch comprising a movable contact member, an off-and-on center spring connected thereto at one end for positioning said contact member either in on-position or off-position, a latch connected to said spring at its other end, and heat responsive means which when subjected to normal temperatures holds said latch in position to exert tension on said spring for

holding said contact member in either on-position or off-position and when subjected to abnormally high temperatures causes said latch to release the tension in said 5 spring whereby the said contact member is precluded from occupying on-position.

5. An electric switch comprising a movable contact member, an on-and-off center 10 spring connected thereto for positioning said contact member either in on-position or off-position, and resoldering means normally exerting tension on said spring when said contact member is either in on-position or off-position, said resoldering means when liquefied releasing the tension in said spring 15 and thereby causing said contact member to move to off-position.

6. An electric switch comprising a movable contact member, an off-and-on center 20 spring connected thereto for positioning said contact member either in on-position or off-position, and a fusible element adapted normally to exert tension on said spring when said contact member is either in on-position 25 or off-position, said fusible element abnormally heated releasing the tension in said spring.

7. An electrical snap switch comprising 30 opposed push buttons, a contact member normally movable into on-and-off positions by actuating said push buttons, and heat responsive means controlling the normal operation of said contact member into on-and-off positions through the agency of said 35 push buttons, said heat responsive means when abnormally heated permitting of the automatic moving of said contact member to off-position.

8. An electrical snap switch comprising 40 opposed push buttons, a contact member normally movable into on-and-off positions by actuating said push buttons, and heat responsive means controlling the normal operation of said contact member into on-and-off 45 positions through the agency of said push buttons, said heat responsive means when abnormally heated permitting of the automatic moving of said contact member to off-position independently of any movement of said opposed push buttons.

9. An electrical snap switch comprising 55 opposed push buttons, a contact member normally movable into on-and-off positions by actuating said push buttons, and heat responsive means controlling the normal operation of said contact member into on-and-off 60 positions through the agency of said push buttons, said heat responsive means when abnormally heated permitting of the automatic moving of said contact member to off-position and automatically releasing it from operative connection with said push buttons until normal temperature conditions are restored in said heat responsive means.

65 10. An electrical snap switch comprising

opposed push buttons, a contact member normally movable into on-and-off positions by actuating said push buttons, and heat responsive means controlling the normal operation of said contact member into on-and-off 70 positions through the agency of said push buttons, said heat responsive means when abnormally heated permitting of the automatic moving of said contact member to off-position and precluding the resetting of said contact member into on-position until the temperature of the heat responsive means is restored to normal.

11. An electrical snap switch comprising 80 opposed push buttons, a contact member normally movable into on-and-off positions by actuating said push buttons, and heat responsive means controlling the normal operation of said contact member into on-and-off 85 positions through the agency of said push buttons, said heat responsive means when abnormally heated permitting of the automatic moving of said contact member to off-position and precluding the resetting of said contact member into on-position through 90 movements of said push buttons until the temperature of said heat responsive means is restored to normal.

12. An electrical snap switch comprising 95 opposed push buttons, a contact member normally movable into on-and-off positions by actuating said push buttons, and a fusible element controlling the normal operation of said contact member into on-and-off 100 positions through the agency of said push buttons, said fusible element when having an abnormally high temperature permitting of the automatic moving of said contact member to off-position and retaining it there independently of any movement of said 105 opposed push buttons.

13. An electrical snap switch comprising 110 opposed push buttons, a contact member normally movable into on-and-off positions by actuating said push buttons, and a fusible element controlling the normal operation of said contact member through the agency of 115 said push buttons, said fusible element when raised to an abnormally high temperature permitting of the moving of said contact member to off-position and discontinuing operative connection between said contact member and said opposed push buttons.

14. An electric switch comprising opposed 120 push buttons, a movable contact member, a spring for normally actuating said contact member by means of said push buttons, heat responsive means, and a connection between said heat responsive means and said opposed push buttons to retain the tension in said spring, said connection being released to move said contact member into off-position when the heat responsive means assumes an abnormally high temperature.

15. An electric switch comprising opposed 130

- push buttons, a movable contact member, a spring normally connecting said contact member to said push buttons, a resoldering element, and a connection between said resoldering element and said contact member for operatively connecting the contact member to said opposed push buttons, said connection being automatically released when the resoldering element is liquefied.
16. An electric switch comprising a movable contact member, an off-and-on center spring connected thereto, opposed push buttons for moving said contact member to off-and-on position, and heat responsive means for controlling the normal operation of said contact member through the agency of said push buttons, said heat responsive means when abnormally heated releasing said contact member from operative connection with said push buttons.
17. An electric switch comprising a movable contact member, opposed push buttons for normally moving said movable contact member to off-and-on positions, heat responsive means operatively connecting said movable contact member to said push buttons, and means automatically disconnecting said movable contact member from operative connection with said push buttons when said heat responsive means is overheated.
18. An electric switch comprising a movable contact member, opposed push buttons for normally moving said movable contact member to off-and-on positions, heat responsive means operatively connecting said movable contact member to said push buttons, and means automatically disconnecting said movable contact member from operative connection with said push buttons during the time only when such heat responsive means is overheated.
19. An electric switch comprising a movable contact member, opposed push buttons for normally moving said movable contact member to off-and-on positions, heat responsive means operatively connecting said movable contact member to said push buttons, and means automatically disconnecting said movable contact member from operative connection with said push buttons and precluding resetting of said contact member in on-position when said heat responsive means is abnormally heated.
20. An electrical switching mechanism comprising a stationary contact member, a movable contact member, a spring element, a fusible element, and a latching member operably associated therewith, said fusible element when in its normal state holding said spring element under tension when said movable contact member is in closed position or open position but allowing said movable contact member to move to open position under the action of said spring when said fusible element is in an abnormal state which causes the latching member to move from its normal position.
21. An electrical switching mechanism comprising a stationary contact member, a movable contact member, a lever, a spring element operably associated with said lever and said movable contact member, a resoldering element, a latching member connecting said resoldering element to said lever, and manually operated means for moving said movable contact member to open or closed position in opposition to the tension exerted by said spring element, said resoldering element when unduly heated releasing said latching member whereby said spring may lose its tension thereby moving said movable contact member to open position, said resoldering element allowing operative connection between said latching member and lever to be restored when said resoldering element becomes cooled.

In witness whereof, I have hereunto subscribed my name.

JOHN S. BAKER.
